UNITED STATES PATENT OFFICE.

BENJAMIN F. WHITE, OF ROCK ISLAND, ILLINOIS.

DESIGN FOR A PORTIÈRE.

No. 38,994.

Specification for Design.

Patented Jan. 7, 1908.

Application filed October 2, 1907. Serial No. 395,648. Term of patent 7 years.

To all whom it may concern:

Be it known that I, BENJAMIN F. WHITE, a citizen of the United States, residing at Rock Island, in the county of Rock Island and State of Illinois, have invented a new, original, and ornamental Design for Portières, of which the following is a specification, reference being had to the accompanying drawing, forming part thereof.

The figure is a perspective view of a portière, showing my new design.

I claim:

The ornamental design for a portière, as shown.

BENJAMIN F. WHITE.
